UNITED STATES PATENT OFFICE.

JOHN HARDMAN, OF NEW YORK, N. Y., ASSIGNOR TO HARDMAN, DOWLING & PECK, OF SAME PLACE.

PIANO-FORTE ACTION-FRAME.

SPECIFICATION forming part of Letters Patent No. 235,357, dated December 14, 1880.

Application filed June 19, 1880. (No model.)

To all whom it may concern:

Be it known that I, JOHN HARDMAN, of the city, county, and State of New York, have invented certain new and useful Improvements 5 in Piano-Fortes, of which the following is a specification.

My invention relates to the movable action-frame in upright piano-fortes, whereby I combine and sustain the frame intact and secure it 10 direct to the iron frame of the piano by a strong and very simple contrivance. The combined frame I arrange so that it may be inclined outward from the other works, or be at once lifted entirely out and removed from the piano for 15 examination or repair independent of any other part, both of which operations are, however, common with other upright pianos, and form no part of my invention.

In drawings, Figure 1 represents a front elevation of my combined action-frame. Fig. 2 shows a side elevation of the same—also, by dotted lines, as thrown back for inspection, in which position it is free to be removed altogether, as stated; and Fig. 3 is a side view of 25 the foot or lower end and step of the standard *a'*.

My improvements consist, first, in the peculiarly-constructed oscillating standards *a a'*, which constitute a part of the frame, as they 30 serve to secure and support the several elements which make up the combined action intact. The standards *a a'* proper consist of single bars slightly waved from a direct line, but are bent inwardly at the head or top end to an angle 35 of, say, forty-five degrees, more or less, which inclined portion is provided with an open perforation or slot at *f*, to receive the lock-bolt *m*. This, being a most important feature in my improvement, combined with the iron frame, will 40 be again referred to. Near the middle of the standards *a a'* a branch or bracket, *b*, curved outward and upward, is shown, and carrying on its end a plate and damper-pad, *l*, to support the combined soft pedal and hammer-rail 45 *i*, made fast to a lever, *i'*, which oscillates on a center of motion through and near to the base of the bracket, at *b'*. This rail *i* is actuated, in the usual manner, by a foot-pedal and elevating-rod at one end, but is not shown in 50 the drawings. A plate, *h*, is shown as cast

onto the standards to hold the action-rail *h'*, and a second plate is shown above *h*, at *k*, to hold the damper-rail *k'*.

So far as described the standards *a a'* are precisely alike; but they differ in construction 55 at their lower ends or feet, which forms my second improvement, as follows: The standard *a* rests at its lower end or foot and rocks upon a short pin, *d'*, secured in a block or otherwise, *d*, at the side of the case. This foot 60 consists of a long toe, *c*, and a short toe, *c'*, the two toes being separated by a slot, *d*, which takes over and oscillates upon the pin *d'*. The toe *c* is made to serve as a check-lever and lock by an auxiliary pin, *e*, fixed in the block or 65 framing near to the pin *d'*, taking against which the toe *c* holds the action-frame in the position shown by dotted lines. It will be seen that either toe may be elongated and turned to take against a fixed pin with like effect. This 70 standard *a* forms one end of the frame, and the opposite end has its duplicate. Between the two standards *a*, at proper intervals, the standards *a'* are fixed, differing from *a* in the form of their feet only, as, instead of the toes and slot, 75 they (*a'*) terminate in angle-points resting in V-grooves, as shown at *a' a'*, Fig. 3. It follows that when released at the top, as shown, the entire action-frame may be lifted out or held in the position as shown in Fig. 2. 80

The third element in my improvements consists in a novel method for securing the action-frame to the main work of the instrument. It is usual in such cases to employ an iron or steel lock-bolt, one end of which is made fast 85 in and at right angles with the wood framework of the piano, the outer end of the bolt holding to the standards by set-screw nuts. Wood in time will shrink, or swell, or warp, or disintegrate in so many cases that it should 90 never be depended on where precision of strength and minute position of parts are imperative. It is for these and other good reasons that I secure my lock-bolts directly into and at a considerable angle with the metal 95 frame or plate of the instrument, as shown at *m B*, Fig. 2. The outer ends of the bolts pass through, regulate, and confine the standards by screw-nuts *n*, at *f*. When the action is lifted from the instrument it may be sus- 100

tained in an upright position by setting the feet of the standards into holes bored in short wooden blocks, as supports, placed transversely with the frame.

5 I do not claim, generally, the use of metallic standards adapted to the frames of upright piano-fortes; nor do I claim the use of oscillating centers for the bottom ends of such standards, nor the securing of such standards by bolts fastened to the wrest-plank or other wood-work of the piano, as all such devices are well known; but

10 What I do claim as my improvement in upright piano-fortes, and desire to secure by Letters Patent, is—

15 1. The inclined head or upper end, *f*, of an action-frame standard, combined with the in-

clined lock-bolt *m*, secured directly into the metallic frame or plate *B*, substantially as described.

20 2. The combination of the movable action-frame, the metal plate *B*, and bolt *m*, constructed and arranged as described, whereby the bolt *m* is secured in an inclined position, substantially as described.

25 3. An action-frame standard for upright piano-fortes, having the curved toes *c c'* and slot *d*, in combination with pin *d'* and check-pin *e'* upon the frame, all constructed and arranged to operate as described.

JOHN HARDMAN.
